UNITED STATES PATENT OFFICE.

ABIJAH B. LATHAM AND PINKNIE F. COOK, JR., OF FELTON, GEORGIA.

DITCHING-MACHINE.

Specification of Letters Patent. Patented Apr. 11, 1916.

1,178,523.

Application filed December 4, 1912. Serial No. 734,923.

To all whom it may concern:

Be it known that we, ABIJAH B. LATHAM and PINKNIE F. COOK, Jr., citizens of the United States residing at Felton, in the county of Haralson and State of Georgia, have invented new and useful Improvements in Ditching-Machines, of which the following is a specification.

This invention relates to ditching machines, and it has for its object to produce a simple and efficient machine for terracing hillsides, for cleaning ditches and for other like uses.

A further object of the invention is to construct a simple and efficient terrace builder and ditch cleaner which may be easily and effectively guided when in operation and which, when not in use, may be folded into small compass for storage and transportation.

With these and other ends in view which will readily appear as the nature of the invention is better understood, the same consists in the improved construction and novel arrangement and combination of parts which will be hereinafter fully described and particularly pointed out in the claim.

In the accompanying drawings has been illustrated a simple and preferred form of the invention, it being, however, understood that no limitation is necessarily made to the precise structural details therein exhibited, but that changes, alterations and modifications within the scope of the claim may be resorted to when desired.

In the drawings,—Figure 1 is a side view of a ditching machine constructed in accordance with the invention. Fig. 2 is a rear elevation of the same. Fig. 3 is a top plan view, showing the machine extended and ready for use.

Corresponding parts in the several figures are denoted by like characters of reference.

The body or center portion of the improved implement consists of a plate 1 having at its forward end a swelled breast portion 2 provided with a downwardly offset curved or rounded earth engaging cutting portion 2', and with an upwardly extending neck 3 having apertures 4 for the attachment of a suitable draft member, not shown. The top and bottom edges of the plate 1 converge rearwardly in rear of the breast portion 2, the rounded earth engaging portion of which projects downwardly a material distance below the lower edge of the plate 1,

the latter being provided with vertical ribs 5 which are forwardly beveled so as to merge with the breast portion.

The center plate 1 is provided with side wings 7, constituting mold boards or ditching blades. These wings are connected with the center plate by means of fastening members 6 consisting of arcuate rods extending loosely through the center plate 1 and also through apertures in the respective wings, said rods being provided with terminal heads 6' which limit the outward swinging movement of the wings, which latter may be folded closely against the center plate, as seen in Fig. 6. The fastening members 6 are arranged in vertical series to the rearward of the ribs 5 from which the several fastening members are equally spaced. The wings 7 are provided near their rear ends 75 with handles 8 whereby they and the implement may be manipulated.

Secured on the inner faces of the wings near the rear ends of the latter, by means of pivots 9, are plates or lugs 10 with which links or braces 11 are hingedly connected, said links being adapted to be extended through the center plate, said links being overlapped with respect to one another, and said links being provided with slots 13 for the passage of a bolt 14, which also extends through an apertured lug 15 on the side of the center plate. It will be readily seen that by means of the bolt 14 the wings may be firmly secured at various adjustments with respect to the center plate, and that by disengaging the slotted brace members or links from the bolts, said brace members may be folded upon the inner faces of the wings, thereby enabling the implement to be folded very compactly for storage or transportation. The links or braces 11 are made tapering or wedge-shaped, as will be clearly seen in Figs. 2, 5 and 8, said links being relatively thin at their outer ends. It follows that when the links are placed in overlapping relation and are connected together by the bolt 14, they will serve to resist external pressure upon the wings 7 and will prevent said wings from collapsing when the machine is in operation.

From the foregoing description taken in connection with the drawings hereto annexed, the operation and advantages of this invention will be readily understood by those skilled in the art to which it appertains. It will be seen that the breast por-

tion of the center plate bulges slightly below the lower edges of the wings, and thus forms a soil engaging cutting member whereby the implement is securely guided when in operation. The wings constitute scrapers whereby the dirt is displaced laterally, as will be readily understood, and it will be seen that the wings may be spaced variously apart at their rear ends and may be securely maintained at various adjustments. For storage and transportation the implement may be folded into small compass. The forward edges of the wings are set in behind the beveled ribs 5 and will, therefore, not obstruct the progress of the machine. The general construction is very simple and inexpensive, and the implement is one of great practical utility.

Having thus described the invention, what is claimed as new, is:—

In a machine of the class described, a center plate having a breast portion with a downwardly offset curved earth engaging cutting portion and vertically disposed beveled ribs defining the breast portion, said breast portion having also an upwardly ex-

tending neck with which draft appliances may be connected, a pair of wings disposed adjacent to the two sides of the center plate with the front edges of said wings abutting on the vertically disposed ribs, an arcuate connecting member extending loosely through the center plate and the wings directly in rear of the front edges of the wings, said connecting member having permanent heads at the ends thereof, and means whereby the wings adjacent to the rearward ends thereof are adjustably connected with each other and with the center plate, the downwardly offset cutting portion of the center plate extending materially below the lower edges of the wings, and said wings being provided with handles whereby they and the machine may be guided and manipulated.

In testimony whereof we affix our signatures in presence of two witnesses.

ABIJAH B. LATHAM.
PINKNIE F. COOK, JR.
